TANK VALVE.

Application filed April 9, 1925. Serial No. 21,936.

Our invention relates to improvements in valves adapted primarily for use in tank cars for transporting oil and the like, and it consists of the constructions, combinations and arrangements herein described and claimed.

An object of the invention is to provide a valve for the purpose described, in which it is an important consideration to make certain engaging parts of non-corrosive metal, and to employ in combination therewith a wiper ring for performing a scraping action in advance of the seating of the valve so that a perfect joint may be insured.

Other objects and advantages appear in the following specification, reference being had to the accompanying drawing, in which—

Figure 1 is a longitudinal section of the improved valve, the closed position being illustrated.

Figure 2 is a combined elevation and sectional view of the valve, being shown in the open position.

Figure 3 is a perspective view of the movable valve head.

Figure 4 is a perspective view of the stationary barrel in which the valve head works.

As already briefly stated, the improved outlet valve is intended primarily for use in connection with tank cars, although its use is not thus confined. The barrel 1 is threaded at 2 to permit screwing into a portion of a spring-type valve which is ordinarily standard equipment on tank cars. A portion of the valve into which the barrel is screwed is shown at 3, details of the valve being omitted because they had no bearing on the invention. A portion of the car is shown at 4. In practice it is optional whether the barrel 1 were screwed in place or provided with a flange that could be welded or otherwise fastened in place.

A circumferential flange 5 provides an abutment for the barrel against the part to which it is secured. A plurality of openings 6 have sharply diverging lower end walls 7. The lower ends of said walls are in the bottom wall of said circumferential flange, the upper ends of the walls producing sharp edges 8 which are intended to keep substances from accumulating on the valve.

A stationary valve seat 9 is inserted in an appropriate recess 10 formed by a reduction in the bore of the barrel 1. This valve seat

may be made of any appropriate metal, but preferably such as is known as Monel metal which has the property of being noncorrosive. The valve seat is beveled at 11, the sharp upper edge merging with the interior upper wall of the barrel and forming part of the sharp edges 8 at the openings 6.

Movable within the barrel 1 is a valve head 12. This valve head is hollow in order to lighten the weight and reduce the amount of materials required in its construction. It has a pair of ears 13 to which a link or rod 14 is suitably attached in order to provide for raising and lowering of the valve head. A pin 15 prevents pulling the valve head out of the barrel should a particularly strong pull be exerted upon the link 14. The upper edge of the valve head is circumferentially grooved at 16 and it is in this groove that the pin engages.

The valve head 12 carries a member 17 which coacts with the stationary valve seat 9. This member is seated in a recess 18 in the lower end of the valve head. It is also preferably made of Monel metal, although other non-corrosive metals may obviously be employed. The cooperating valve member 17 is beveled to match the bevel 11 of the seat 9 and when the two parts engage as in Figure 1 a perfectly tight joint as in Figure 1 results.

A resilient ring 19 causes a scraping action upon the valve seat 9 when the valve head 12 is moved downward to the seating position. This ring has a lap joint 20 commonly seen in piston rings. This ring is also preferably made of Monel metal, or of such material as will not corrode.

In operating the valve head 12 is simply raised and lowered to respectively open and close the valve. When lowered, the expanded ring 19 (Fig. 2) will ride upon the bevel 11 of the seat 9 and become contracted until it assumes the position in Figure 1. The contracting action of the ring 19 produces a scraping action upon the bevel 11. Any accumulation that may have gathered upon the stationary valve seat is therefore loosened and will be carried out when the valve head 12 is again raised.

The engagement of valve member 17 with the bevel 11 of the stationary seat 9 will alone produce a tight joint, but when the expandible ring 19 is combined therewith the resulting joint becomes such as will insure against any possibility of leakage. It

is to be borne in mind that the joint is produced by a combination of surfaces upon which downward and lateral pressures are exerted. First occurs in the instance of the 5 engagement of the member 17 with the bevel 11 of the seat 9, while the second occurs in the instance of the laterally expanding ring 19 against the internal wall of the seat. A further feature of importance resides 10 in the provision of a groove 21 at the head of the recess 18 and immediately above the valve member 17. This groove exposes the peripheral edge of the member 17 and makes 15 room for the admission of fluid from the tank car. This fluid obviously produces a downward pressure which, when exerted upon the exposed edge of the member 17, tends to exert pressure upon the member 17 in addition to that imposed by the weight of 20 the head 12 and its actuating members.

While the construction and arrangement 25 of the improved tank valve is that of a generally preferred form, obviously modifications and changes may be made without departing from the spirit of the invention or 30 the scope of the claims.

We claim:—

1. A valve comprising a barrel having a beveled valve seat, a relatively movable valve head, and annular resilient means carried by the head which is contractible as it moves over the beveled seat when the valve head is being moved to a closing position to scrape any obstructions from the seat.
2. A valve comprising a barrel having a beveled valve seat, a relatively movable valve head, a member carried by the head to cooperate with the seat and being correspondingly beveled to produce a tight joint 40 when the valve is closed, and annular resilient means carried by said member being contractible as it moves over the beveled seat to scrape the surface in advance of the engagement of said member.
3. A valve comprising a barrel having a beveled seat, a relatively movable valve head, a member carried by the head being beveled to correspond and coact with the beveled seat to make a tight joint when the 50 valve is closed, and a split ring carried by said member being compressible upon moving over the beveled seat to scrape the surface in advance of the member and then closely engaging the seat to assist in making said joint.
4. A valve comprising a barrel having a beveled seat, a valve head having a recess and an adjoining peripheral groove, a circumferential member seated in the recess 60 being beveled to correspond and cooperate

with said beveled seat to make a tight joint when the valve is closed, a portion of said member protruding at said groove to receive the thrust of fluid pressure to insure said joint.

5. A valve comprising a barrel having a plurality of openings the lower walls of which are beveled to produce sharp edges, a seat carried internally of said barrel being beveled and having the upper end coinciding 70 with and assisting in the formation of said sharp edges, the beveled portions preventing substances lodging in the openings, a valve head which is relatively movable inside of the barrel, a recess in said head having an adjoining circumferential groove, and a circumferential member seated in said recess being beveled to correspond with the beveled seat and having a portion protruding circumferentially in said groove to receive 75 the thrust of fluid pressure entering at said openings to force said member upon said seat.

6. A valve comprising a barrel having a recess, a seat of material dissimilar to the 80 barrel occupying the recess and being beveled, a valve head relatively movable inside of the barrel having a recess, a member of material dissimilar to the valve head occupying said recess and being beveled to 85 match the bevel of the seat, and an expandable and contractible ring carried by said member being of material similar to that of the member.

7. A valve comprising a barrel having a 90 plurality of openings and a circumferential flange providing beveled walls for the bottom of the openings and producing sharp edges at the interior of the barrel, the bore of the barrel being reduced to form a recess 100 therein, a seat in said recess being beveled and meeting said sharp edges, a valve head fitting the barrel having a recess at the lower end and an adjacent circumferential groove, a grooved member occupying the 105 recess and being beveled to correspond with the valve seat, a circumferential portion of said member protruding at the circumferential groove permitting the fluid pressure through said openings to assist seating the valve head, means for moving the valve head in the barrel, and a contractible and expandable ring in the groove of said member scraping over the beveled valve seat as the head is moved to insure a clean surface for 110 said member and then engaging the valve seat to complete the joint.
